RAILROAD CAR TRUCK AND BRAKE
CONSTRUCTION

Harry A. Mills, Grand Rapids, Mich.

Application March 5, 1934, Serial No. 714,050

9 Claims. (Cl. 188—53)

This invention relates to railroad car trucks and the brake construction carried thereby. It is a primary object and purpose of the present invention to provide a much simpler, more practical and considerably cheaper construction of car truck and brake mounting and operating means therefor, for use on railroad cars. A further object of the invention is to provide such a construction, eliminating numerous parts heretofore used and which have been considered necessary, and to further provide a construction wherein disassembly for purposes of repair and replacement is attained in the most simple, practical and economical manner, and with the removal or disconnecting of a minimum of parts. One very marked advantage with my invention is a complete elimination of the transverse brake beams now used, which are pivotally suspended on pivot pins. These pivot pins quite frequently are jolted loose or otherwise become disconnected whereupon the brake beam drops downwardly at its disconnected end and strikes against and tears up the track with, of course, great damage and injury to the entire braking mechanism.

Many other objects and purposes than those stated and novel constructions for attaining the same, together with the provision of a braking mechanism and operating means therefor which is located at a much higher plane than previously so that there is no chance for the same to strike against the railroad bed or ties, nor any brake beams to drop down and strike the railroad bed, will be apparent as an understanding of the invention is had from the following description, taken in connection with the accompanying drawings, in which,

Fig. 1 is a side elevation of the car truck with my invention applied thereto.

Fig. 2 is a plan view of the car truck and braking mechanism of my invention.

Fig. 3 is a fragmentary enlarged vertical section substantially on the plane of line 3—3 of Fig. 2 looking in the direction of the arrows.

Fig. 4 is a fragmentary horizontal section and plan substantially on the plane of the line 4—4 of Fig. 3 looking downwardly.

Fig. 5 is a fragmentary vertical section substantially on the plane of line 5—5 of Fig. 4.

Fig. 6 is a fragmentary transverse section on line 6—6 of Fig. 2.

Fig. 7 is a like vertical transverse section on the line 7—7 of Fig. 2, the direction of the views in Figs. 6 and 7 being indicated by the arrows.

Fig. 8 is a perspective view of the bolster carry-

ing yoke used, one for each end of the bolster and carried by a truck side frame.

Fig. 9 is a fragmentary section illustrating the manner of mounting a support for a link which is utilized in operating the brakes.

Fig. 10 is a diagrammatic plan view showing the manner in which the truck side frame may be readily removed.

Fig. 11 is a section similar to Fig. 2 illustrating my invention applied to the side frames of trucks now used on railroads, and

Fig. 12 is a fragmentary end elevation of the structure shown in Fig. 1.

Like reference characters refer to like parts in the different figures of the drawings.

The truck used for carrying railroad cars includes two side truck frames 1, which at each end are provided with journal boxes 2 to receive the end portions of axles 3 which rotate therein, each axle carrying a pair of car wheels 4 spaced apart from each other proper distances to ride on railroad tracks.

A truck side frame 1 at its intermediate portion includes an upper horizontal member 6, a lower horizontal member 7 with spaced apart vertical members 8, making a rectangular frame structure surrounding a rectangular opening. Between the two side frame members of a truck a horizontally located spring pan 9 is disposed, resting at its ends upon the lower horizontal parts 7, which preferably in their upper sides (Fig. 6) have depressions therein to receive downwardly projecting embossings 9a from the bottom of the spring pan 9 and thus hold the spring pan from endwise movement. The spring pan is preferably of a channel shape having a horizontal web and upturned side flanges.

Assemblies of coiled springs are mounted on the spring pan at the end portions thereof directly over the horizontal portions 7 of the side frames, each including a metal member 10 against which the lower ends of heavy coiled springs 11 bear, their upper ends bearing against a similar member 12. In practice there are usually four of the coiled springs in each spring assembly. A bolster 13 extends between the side frame members of the truck and bears at its end portions on the upper part 12 of the spring assemblies, the upper side of the end portions of the bolster coming against the lower sides of the horizontal upper members 6 of the frames as shown in Fig. 3.

With my invention a metal yoke is provided to embrace and locate each end of the bolster 13. The yoke (Fig. 8) has a horizontal lower side 14 with upwardly extending vertical ends 15. The

lower side or bottom of the yoke is cut away to make a recessed portion of a width equal to the width of the bolster at the ends where the yoke is placed, as indicated at 14a; and the vertical parts 15 are likewise recessed at their outer sides making in each a relatively wide vertical guide groove 16. At each lower corner of the yoke there is also provided outwardly extending lugs 17. The inner sides of the vertical parts 8 of the truck side frame previously described are formed with metal guide ribs 18 of a proper shape to be received within the guide grooves 16 of the yoke. Such members 18 extend downwardly below the yoke when it is in its operative position as shown in Fig. 3. The bolster 13 at each side and at each end thereof is provided with vertical spaced apart ribs 19 between which the vertical sides 15 of the yoke are slidably received, and the bolster at its lower side is cut away substantially the thickness of the bottom 14 of the yoke making a recess into which said bottom enters, as shown in Fig. 6.

In assembling the bolster, supporting yokes therefor and the truck side frame members, the yoke is located so as to rest upon the spring pan 9, the bolster entered thereinto and then the bolster and yoke are elevated to their upper position as shown in Fig. 1. Thereafter the spring assembly, consisting of the springs 11 and the parts 10 and 12 is put in place. A block or shim indicated at 10a is many times used underneath the lower member 10 of the spring assembly. After the yoke has been assembled in place and engaged with the guide ribs 18, stops 20 are welded or otherwise secured to the inner sides of the vertical members 8 in a position such as to prevent the yoke dropping down far enough to completely disengage from the ribs 18, when the springs are removed. However, the supporting yoke is permitted to lower far enough that, when supported on the stops 20, the bolster may be lifted above the yokes so as to disengage therefrom, whereupon the bolster may be readily moved lengthwise to disengage at one end from a side frame 45 of the truck and then tilted and moved longitudinally the other way to disengage the opposite end, this being indicated in dotted lines in Fig. 7. This leaves the spring pan 9 in place and there are no parts of the mechanism for operating the brakes connected in any manner to the bolster which when once disengaged from the yokes described may be readily removed or as readily replaced. This provides a very simple and practical assembly and is very convenient for disassembly and removal of the bolster when desired, as in cases of repair or replacement.

The brakes and the operating means therefor are carried by the truck side frames. Integral supporting bosses 21 and 22 are cast with the side truck frames so as to extend inwardly (Fig. 2) at each side of and slightly above the spring pan 9. A plate 23 is disposed between the supporting bosses 21 and 22 (Figs. 3 and 4). Such plate at one end is narrowed, at 24, for reception in a slot cut in the part 22, and at the other end has a projecting narrowed portion 25 which passes through a suitable slot cut in the part 21 and is secured thereto as by a pin 26. As shown in Fig. 4, the part 21 is cut away to permit swinging movement of the plate 23 during its disassembly. The plate 24 is provided with a rectangular opening 27 (Fig. 4) as shown. From each side of the plate 24 directly over the spring pan 9 (Fig. 3) downwardly extending sides 28

are provided, each formed with a horizontal slot 29 therein near the lower edge of the side.

Brake shoes 30 each detachably mounted and installed upon the usual conventional brake head 21 are carried at the outer ends of bars 32 and 33 respectively, which are horizontally located and slidably mounted upon and extend through the bosses 21 and 22, respectively. The bars 32 and 33 extend toward each other and at their inner ends pass above the sides of the spring pan 9. A block 34 of metal is mounted on and between the sides 28 previously described on a pin or rod 35 which passes therethrough and through the slots 29 in the sides 28. Its upper portion passes through the opening 27 in the plate 23, and is provided with a dog 36 at one side which stops turning movement of the block 34 about the pin 35 when the same engages against the plate 23, as shown in Fig. 5. Said block 34 in its under side is slotted to provide a slot 37 into which the inner end of the bar 32 extends. A link 38 is pivotally connected at one end to the inner end of the bar 32, and is connected at its opposite end, by means of a pivot pin 39, to the block 34 below the pin 35. The inner end of the other bar 33 is pivotally connected to one end of a similar link 40 which is pivotally connected to the block 34 by a pin 41, located above the pivot 35 a distance equal to that of the pin 39 below the pivot 35.

It will be apparent that on turning the block 34 upwardly about its pivot 35 there is a simultaneous and equal outward movement of the rods 32 in opposite directions and 33 which brings the brake shoes 30 against the car wheels 4. It is also evident that by reason of the slot at 29, if one brake shoe 30 is thinner than the other or has been worn more than the other, though the thicker brake shoe may come to a wheel ahead of the thinner shoe, the pin 35 by its movement permitted in the slots 29 will automatically move to a position such that the engagement of the brake shoes 30 against the wheels will be with equal pressure until such time that one brake shoe is enough thinner than the other that the pin 35 come to one end of the slots 29, whereupon the thinner brake shoe will not thereafter bear against the car wheel with which it is associated and will not thereafter wear, thus safeguarding against any grinding off or damage to the brake head 31 in which the shoe is mounted. When such action occurs, the thin brake shoe is substantially worn out and should be replaced by another.

In turning the member 34 about its pivot 35 to set the brakes, a pull rod 42 is used at one end having a plurality of spaced apart openings 43 for passing a pin 44 therethrough and through the member 34, as shown in Fig. 5, the holes 43 permitting a limited range of adjustment. The pull rod 42 is connected to a link 45 at a joint between the ends of the link. The link 45 at its outer end is pivoted to ears 46 cast integral with and extending from the adjacent vertical member 8 of the side frame of the truck. The link extends from the ears 46 upwardly and inwardly. There being two of the links 45, one for each side of the truck, the inner ends of the same are connected to the ends of an arc-shaped equalizer yoke 47 by a pin and slot connection 70 shown at 48. Rod 49 is attached at the midpoint of yoke 47 and from thence extends to the air mechanism which when operated exerts a longitudinal pull on the rod 49 in a direction to the right, as shown in Fig. 2, and in any event 75

in a direction away from the truck toward the compressed air motive power. The block 34, see Fig. 5, tends to turn counterclockwise due to the eccentric pivot 35 and thus this gravitational effect aids in withdrawing the brake shoes to inoperative position.

The links 45 are supported inwardly from their points of connection to the pull rods 42 on link supports 50, which are mounted upon spaced apart ears 22a extending horizontally inward from the bosses 22. The supporting standards for the supports 50 at their lower ends are equipped with cylindrical projections 51 and between the ends of the cylindrical portions 51 each 15 with a part 52 which is rectangular in cross section. The lower ear 22a has a recess to receive the lower end of the part 52 thereby holding the same from rotative movement. By lifting the link support 50 a short distance so as to raise 20 the part 52 above its recess, the support may be turned to the dotted line position shown in Fig. 2, thus permitting the support 50 to pass by the adjacent wheel 4 which it would otherwise strike if it was held in the full line position shown in 25 Fig. 2.

The construction described is one which permits very easy disassembly. For example if a side truck frame is to be removed there is one pin only which needs to be removed. That is, 30 the pin at the inner end of the link 45 which connects such link with the equalizing yoke 47. Then by turning the link support 50 to the dotted line position shown in Fig. 2, withdrawing the spring assembly from beneath the end of the bolster, and dropping the bolster yoke down until the same rests upon the stops 20, the entire side frame member of the truck with the brakes and associated operating mechanism mounted thereon may be removed. It is, of course, to be understood that in such removal some auxiliary means 40 for holding or supporting the bolster 13 and the spring pan 9 will be used such as an overhead chain, or blocks underneath the spring pan and bolster. Either side of the truck frame may 45 be very simply and easily removed and any repairs which are necessary thereon can then be accomplished. The return of the side frame of the truck with the brakes carried thereby is quite as easily and simply accomplished.

50 It will further be observed that all operating mechanism for the brakes is at a relatively high position. There is no operating mechanism which extends downwardly, and nothing like that very largely if not universally in use at the present time which extends below the level of the spring pan and quite close to the road bed, and which is a cause of considerable injury or destruction to the brake mechanism by reason of striking against a part of the road bed which may be lifted above 55 where it should be. It is further evident that the cumbersome brake beams now used which extend from the inner side of one side of the truck toward the other side and are carried by and between the side frame members of the truck, are wholly eliminated. Such elimination of brake beams removes the danger which is present and which occurs frequently of accidental disconnection of the pins from which the beams are suspended and eliminates the brake beam dropping down to strike the road bed with resultant 60 damage to the road bed, destruction of the brake mechanism and danger of wrecking a train. Such elimination of brake beams and other parts obviates the necessity of a great deal of disassembly which has previously been necessary. In

order to remove the side frames of the truck the spring pan, brake beams, safety irons, brake shoes and brake levers and lower brake rods have to be disconnected and removed, with a removal of numerous pivot pins and with a likelihood of loss of some of the parts before reassembly took place.

The structure which I have produced permits the use of permanent pivot pins, none of which have to be removed for disassembling a side frame member of a truck except that at 48. It is also 10 evident that the major portion of the mechanism is located directly above the pan 9 and if any pivot or connecting pin, such as 35, 39, 41 and 44 should for any reason become disconnected from the parts with which associated, the same drop 15 down into and are held by the pan 9. The construction is thus one of a very useful, simple, practical and economical nature.

While I have shown and described the preferred embodiment of my invention and the manner in 20 which I prefer to build the same where it is built new, my invention is readily applicable to trucks of cars now in use. Such trucks at their inner sides are provided with brackets 53 (Figs. 11 and 12) from which brake beams which carry the 25 brake shoes are suspended. In applying my invention to present day truck construction such brake beams and the parts carried thereby are removed and members 54 and 55 are mounted on said brackets as by rods or pins 56. Such members 30 54 and 55 occupy the same position, serve the same purpose and are equivalent in use to the bosses 21 and 22 previously described. They carry the bars 32 and 33 respectively, and between the same the plate 23 is mounted carrying the 35 various elements 34, the links 38 and 40 and the like. The only addition which has to be made to the truck frame member is the welding or otherwise permanent attachment of the ears 46 to a vertical member, corresponding to the part 8 of 40 the truck frame member, on which to pivotally mount the link 45. With such construction the brake beams and the manner of carrying the brakes thereby are eliminated and essentially the same results are obtained using the same brake 45 setting and operating mechanism. This change in structure is fully shown in Figs. 11 and 12, and with such structure the same simplicity of operation, readiness and ease of disassembly for replacement and repair, cheapness of construction 50 and the like are attained as in the first described structure.

The invention is defined in the appended claims and is to be considered comprehensive of all forms of structure coming within their scope.

I claim:

1. In a construction having spaced axles with wheels thereon and truck frames at opposite ends of the axles, said truck frames being removable by movement outwardly in a direction parallel to 60 the axes of the axles, said truck frames having extensions thereon, braking means mounted upon said extensions, link mechanism for operating the braking mechanism, means for connecting the link means onto the braking mechanism, and 65 means for supporting in part the operating means for the brake mechanism, this means extending interiorly of the wheels, and means for supporting the supporting means for pivotal movement for the purpose described.

2. In combination, two spaced truck frames, wheel and axle constructions mounted at the opposite ends of said truck frame to hold the frames in parallel positions and also to revolubly mount the said axles, a bolster removably mounted in 70 75

the truck frames, braking mechanisms for the respective wheels, and means for operating the braking mechanism including lever members, means for pivoting one end of said lever members onto the respective truck frames and actuating means connected at the other end of the said lever members, said lever members being located in the same horizontal plane as the bolster at all points located between the respective 10 wheels whereby they are protected and shielded from injury.

3. A combination of elements as set forth in claim 2 in which a link support is provided for each of said levers, and means on the respective 15 truck frames for supporting said levers.

4. A combination of elements as set forth in claim 2 in which means is provided for supporting the said members for horizontal movement, said supporting means having a mounting where-20 by it may be lifted to provide both pivotal and universal movement thereof for the purpose de- 20 scribed.

5. In combination, a truck frame having journals at opposite ends thereof, axles carrying wheels 25 mounted in said journals, said truck frame having extensions extending into the plane of the said wheels, said wheels being in the same plane, a plate mounted upon said extensions, braking means mounted upon said plate and means for 30 operating said braking means.

6. The combination of elements as set forth in claim 5 in which the plate is pivotally mounted

upon one end and detachably connected upon the other end for the purpose described.

7. In a device having two wheels and means for revolubly mounting the same in the same plane in spaced apart relationship, the combination of, a block, a brake shoe for each wheel, linkage between each brake shoe and the block, means for pivotally mounting said block whereby movement about its pivot causes actuation of the brake shoes, said block being eccentrically located about said pivot whereby gravity aids in releasing the said shoes from the wheels. 10

8. In a side truck frame having extensions thereon, the combination of a braking mechanism mounted on said extensions, said braking mechanism including a plate mounted upon said extensions, said plate having depending portions at opposite sides, a block pivoted between said depending portions, brake shoes located at opposite ends of said block and linkage connected onto 20 the respective brake shoes, one of said sets of linkage being pivoted onto the block at one side of its pivot and the other set of linkage being connected onto the block at the opposite side of said pivot for the purpose described. 25

9. A combination of elements as set forth in claim 8 in which the pivot between the depending portions and the block permits longitudinal movement whereby the pressure on the brake shoes will be equalized. 30

HARRY A. MILLS.
